SAFETY COUPLING

John Piper, Uniontown, Pa., assignor of one-fourth to Abe Cohen and one-fourth to Max Cohen, Uniontown, Pa.

Application July 3, 1940, Serial No. 343,851

5 Claims. (Cl. 213—20)

The present invention relates to new and useful improvements in couplings for mine cars and similar vehicles in which the respective sections of the coupling may be automatically secured in position for coupling the cars together without necessitating a person entering between the cars, as well as providing means for releasing the coupling mechanism alongside of the cars and the primary object of the present invention is to provide a pivoted coupling stem carried by one of the cars to enable the free turning movement of the adjacent cars as the same are rounding a curve in the track and also to provide means for maintaining the coupling stem in the desired position for coupling cars positioned on a curve in the track.

A still further object is to provide a device of this character of simple and practical construction, which is efficient and reliable in performance, relatively inexpensive to manufacture and maintain in operation and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a top plan view of the adjacent ends of a pair of cars in position the same would occupy relative to each other when on a curved track.

Figure 2 is a bottom plan view of the housing for the coupling stem,

Figure 3 is a longitudinal sectional view therethrough, and

Figure 4 is a horizontal sectional view thereof.

Referring now to the drawings in detail, wherefore in the purpose of illustration I have disclosed a preferred embodiment of the invention, the numerals 5 and 6 designate a pair of mine cars of conventional construction, one end of the car 5 being provided with the female coupling member 7, of a type covered in my application Serial No. 278,345, while the adjacent end of the car 6 is provided with the male part of the coupling member designated at 8.

The coupling member 8 includes a housing 9 comprising upper and lower plates 10 and 11, respectively, secured to the end of the car by means of bolts 12, a portion of the plate projecting outwardly from said end of the car as shown in Figure 1 of the drawings.

The outwardly projected end of the coupling 8 is

curved and provided with a horizontally extending slotted opening 13 having flanges 14 secured at the edge portions thereof and projecting through the opening is the coupling stem 15 having the cylindrical coupling head 16 at the outer end 5 thereof for insertion into and engagement by the female coupling member 7.

The inner end of the stem 15 is reduced as shown at 17 and is slidably mounted in the bore 18 of a socket member 19 which is formed with 10 upwardly and downwardly extending trunnions 20 and 21 respectively, journaled in openings formed in the upper and lower plates 10 and 11, respectively, as shown in Figure 3 of the drawings.

The socket member 19 is formed with forwardly extending spaced parallel arms 22 between which the stem 15 is freely positioned, the stem being provided with a coiled spring 23 for yieldably projecting the stem outwardly, the stem being provided with upwardly and downwardly 20 extending pins 24 and 25, respectively, adapted to abut the inner edge of the flanges 14 to limit outward movement of the stem. Also as shown to advantage in Figure 4 of the drawings, the inner edges of the flanges 14 are curved to facilitate the 25 riding of the pins 24 and 25 along said flanges during the swinging movement of the stem. The stem is normally maintained in a centrally disposed position in the slotted opening 13 by means of coiled springs 26 and 27 attached to the arms 30 22 and 23, respectively, one end of each of said springs being anchored to an adjacent side of the housing 8.

The lower end of the trunnion 21 is formed with a square-shaped extension 28 to which the 35 rear end of a forwardly extending arm 29 is attached, the forward end of the arm having one end of a link 30 pivotally connected thereto, the link extending laterally beyond one side of the housing 9 and to its outer end is attached a lever 40 31 which is accessible from a position at the side of the car to enable horizontal pivotal manipulation of the stem without necessitating the hand of the workman being placed between the cars.

Accordingly, the stem may be swung into the 45 desired position for coupling with the coupling member of an adjacent car when the cars are on a curved track.

It is believed the details of construction, advantages and manner of use of the device will be 50 readily understood from the foregoing without further detailed explanation.

Having thus described the invention, what I claim is—

1. A vehicle coupling comprising a female cou-

55

pling member and a male coupling member, said male coupling member comprising a casing secured to the vehicle, a pivoted member in the casing, a stem having one end reciprocally mounted in the member and having its opposite end projecting outwardly of the casing, spring means yieldably maintaining the stem in a longitudinally extended position, stop means limiting longitudinal extension of said stem and manually operated means attached to the pivoted member for swinging the outer end of the stem horizontally.

2. A vehicle coupling comprising a female coupling member and a male coupling member, said male coupling member comprising a casing secured to the vehicle, a pivoted member in the casing, a stem having one end reciprocally mounted in the member and having its opposite end projecting outwardly of the casing, spring means yieldably maintaining the stem in a longitudinally extended position, stop means limiting longitudinal extension of said stem and a manually operated lever at one side of the vehicle and operatively connected to the pivoted member for swinging the outer end of the stem horizontally.

3. A vehicle coupling comprising a female coupling member and a male coupling member, said male coupling member comprising a casing secured to the vehicle, said casing having a horizontal slotted opening therein, a stem having one end projecting outwardly through said opening, a socket having oppositely extending trunnions journaled in the casing, a bore in the socket slidably receiving the inner end of the stem, spring means yieldably urging the stem outwardly, spring means yieldably maintaining the stem in a longitudinally extending position, stop means limiting longitudinal extension of said stem and

manually operable means attached to the socket to swing the stem horizontally.

4. A vehicle coupling comprising a female coupling member and a male coupling member, said male coupling member comprising a casing secured to the vehicle, said casing having a horizontal slotted opening therein, a stem having one end projecting outwardly through said opening, an arcuate flange in the casing adjacent the opening, a socket having oppositely extending trunnions journaled in the casing, a bore in the socket slidably receiving the inner end of the stem, spring means yieldably urging the stem outwardly, a lateral pin on the stem engaging the flange to limit outward movement of the stem, spring means yieldably maintaining the stem in a longitudinally extending position and manually operable means attached to the socket to swing the stem horizontally.

5. A vehicle coupling comprising a female coupling member and a male coupling member, said male coupling member comprising a casing secured to the vehicle, said casing having a horizontal slotted opening therein, a stem having one end projecting outwardly through said opening, an arcuate flange in the casing adjacent the opening, a socket having oppositely extending trunnions journaled in the casing, a bore in the socket slidably receiving the inner end of the stem, spring means yieldably urging the stem outwardly, a lateral pin on the stem engaging the flange to limit outward movement of the stem, spring means yieldably maintaining the stem in a longitudinally extending position, one of said trunnions projecting from the casing and a manually operable lever connected to the outer end of the trunnion for swinging the stem horizontally.

JOHN PIPER.
